Patented Dec. 5, 1916.

UNITED STATES PATENT OFFICE.

ERNEST FUCHS, OF BILLANCOURT, FRANCE, ASSIGNOR TO LOUIS RENAULT, OF BILLANCOURT, FRANCE.

STARTING DEVICE FOR INTERNAL-COMBUSTION ENGINES.

1,207,157.

Specification of Letters Patent.

Patented Dec. 5, 1916.

Application filed February 1, 1915. Serial No. 5,568.

To all whom it may concern:

Be it known that I, ERNEST FUCHS, citizen of the French Republic, residing at Billancourt, Department of the Seine, in France, have invented certain new and useful Improvements in or Relating to Starting Devices for Internal-Combustion Engines; and I do hereby declare the following to be a full, clear, and exact description of the invention, such as will enable others skilled in the art to which it appertains to make and use the same.

This invention relates to the starting of internal combustion engines by means of an auxiliary electric motor.

In the method of mounting which forms the subject of the invention, the auxiliary motor is adapted to oscillate or rock upon its support for the purpose of being brought nearer to or separated from the flywheel of the engine, so as to permit the engagement or disengagement of teeth, rollers and the like, carried by the electric motor and the flywheel, respectively.

The auxiliary motor is kept in the starting and inoperative positions by means of two stops against which it is caused to abut by means of a spring arranged in such a manner that the disengagement of the auxiliary motor may take place automatically by oscillating or rocking about its support as soon as the engine has started.

The invention comprises in addition thereto, other features which will be described hereinafter.

In the accompanying drawing:—Figure 1 is a diagrammatic view of the mounting of the starting motor which in the present case is an electric motor. Fig. 2 is a side view thereof. Fig. 3 is an enlarged detail illustrating the switch which is used to close the motor circuit.

1 designates the flywheel of the internal combustion engine; this flywheel carries on its periphery a toothed wheel 2 adapted to mesh with another toothed wheel 3 mounted on the shaft of the electric motor 4 which in general, is actuated from accumulators. The motor 4 is mounted so as to be rockable about a stationary axis 5 and is integral with an arm 6 adapted to bear either on the fixed stop 7 or on the fixed stop 8. The two stops 7 and 8 are integral with the chassis. A suitable spring 9 fixed at one end to a fixed point 10 of the chassis

and at the other, in proximity to the end of the lever 6, causes the same to bear energetically either on the stop 7 or on the stop 8. In order to obtain this result, the axis 5 is located within the triangle constituted by the points 7, 8, and 10. The embodiment of the switch shown in the drawing, Fig. 3, includes a switch blade 13 which is secured to but insulated from the arm 6 and moves therewith. This blade is adapted to extend into and bridge a pair of sockets 14 which form the terminals of the motor circuit and to which wires 15 are connected. The specific construction of this switch, however, forms no part of the present invention, as it is only essential that it be of such type that the bridging blade may be readily disengaged from the terminal sockets. When the arm 6 bears on the stop 7 as illustrated in Fig. 1, the toothed wheels 2 and 3 are in engagement; this is the position which corresponds to the starting of the internal-combustion engine by the electric motor. When the arm 6 bears on the stop 8, however, the gears 2 and 3 are out of engagement.

The starting device operates in the following manner:—The direction of rotation of the electric motor is indicated by the arrow 11 while the direction of rotation of the engine is indicated by the arrow 12. For starting purposes, the arm 6 is brought into the position shown in Fig. 1 in which it bears on the stop 7; the gears 2 and 3 are in engagement. On viewing Fig. 1, it will be perceived that the direction of rotation of the electric motor and the resistance of the flywheel cause the arm 6 to bear strongly on the stop 7, consequently the rotation of the motor 4 operates the flywheel 1 and starts the internal combustion engine. As soon as the engine is working, it would rotate the electric motor at too high a speed if the engagement of the gears 2 and 3 were maintained, but owing to the rotation of the engine, the electric motor rocks about the axis 5 and as soon as the dead-point is passed, the spring 9 causes the arm 6 to bear strongly on the stop 8 so that there is no fear of the gear wheels 2 and 3 coming again into engagement.

The oscillatory or rocking movement being very rapid, the same is used to obtain a sudden operation of the starting switch for the electric motor. Similarly, an oscillatory movement of the motor in the opposite di-

rection, can be utilized for supplying current to this motor.

Briefly the operation is limited to bringing the arm 6 to bear on the stop 7 by any suitable means; the effect of this movement is to cause the gear wheels 2 and 3 to mesh and at the same time to supply current to the electric motor and once the engine is started the disengagement of the gear wheels 2 and 3 and the cutting off of the current are effected automatically by the simple rocking movement of the arm 6 toward the stop 8.

It is obvious that instead of the gear wheels 2 and 3 friction rollers or any other connecting means may be employed.

Having now particularly described and ascertained the nature of my said invention and in what manner the same is to be performed, I declare that what I claim is:

1. The combination with a rotary part of an internal combustion engine, of an electric starting motor for the engine, a support upon which said motor is pivotally mounted to swing into and out of operative position with respect to said rotary part of the engine, said support being so positioned that when the engine is started the motor will be automatically shifted toward its inoperative position, and means tending to yieldingly retain the motor in either of its positions.

2. The combination with a rotary part of an internal combustion engine, of an electric starting motor for the engine, a support upon which said motor is pivotally mounted to swing into and out of operative position with respect to said rotary part of the engine, said support being so positioned that when the engine is started the motor will be automatically shifted toward its inoperative position, a pair of stops against one of which a part of the motor abuts in either of its positions, and means tending to yieldingly retain the motor in either of its positions against the corresponding stop.

3. The combination with a rotary part of an internal combustion engine, of an electric starting motor for the engine, a support upon which said motor is pivotally mounted to swing into and out of operative position with respect to said rotary part of the engine, said support being so positioned that when the engine is started the motor will be automatically shifted toward its inoperative

position, an arm mounted to move with the motor, a pair of stops against one of which said arm abuts in either position of the motor, and means tending to yieldingly retain the motor in either of its positions with said arm against the corresponding stop.

4. The combination with a rotary part of an internal combustion engine, of an electric starting motor for the engine, a support upon which said motor is pivotally mounted to swing into and out of operative position with respect to said rotary part of the engine, said support being so positioned that when the engine is started the motor will be automatically shifted toward its inoperative position, an arm projecting upwardly from the motor and mounted to swing therewith, a pair of stops against one of which said arm abuts in either position of the motor, and a spring acting on said arm and secured at a fixed point between said stops and below the axis of oscillation of said arm whereby said spring tends to yieldingly retain the motor in either of its positions.

5. The combination with a rotary part of an internal combustion engine, of an electric starting motor for the engine, a support upon which said motor is pivotally mounted to swing into and out of operative position with respect to said rotary part of the engine, said support being so positioned that when the engine is started the motor will be automatically shifted toward its inoperative position, an arm projecting upwardly from the motor and mounted to swing therewith, a pair of stops against one of which said arm abuts in either position of the motor, a spring acting on said arm and secured at a fixed point between said stops and below the axis of oscillation of said arm whereby said spring tends to yieldingly retain the motor in either of its positions, an electric switch controlled by the movement of said arm, and an electric circuit in which said motor is connected, said circuit being closed by said switch when the motor moves to its operative position and opened by said switch when the motor moves to its inoperative position.

In testimony whereof I affix my signature, in presence of two witnesses.

E. FUCHS.
